UNITED STATES PATENT OFFICE.

MAX MEEPOS, OF SAN ANTONIO, TEXAS.

PERMUTATION-LOCK.

1,117,417.

Specification of Letters Patent.

Patented Nov. 17, 1914.

Application filed January 7, 1914. Serial No. 810,807.

To all whom it may concern:

Be it known that I, MAX MEEPOS, a citizen of the United States, residing at San Antonio, in the county of Bexar and State of Texas, have invented a new and useful 5 Permutation-Lock, of which the following is a specification.

The device forming the subject matter of this application is a permutation lock, and 10 one object of the invention is to improve the permutation mechanism thereof and to provide novel means whereby the combination of the lock may be changed.

Another object of the invention is to provide locking mechanism which coöperates in a novel manner with the permutation structure.

It is within the scope of the invention to improve generally and to enhance the utility 20 of, devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made 30 within the scope of what is claimed without departing from the spirit of the invention.

In the accompanying drawing:—Figure 1 shows the invention in side elevation; Fig. 2 is a longitudinal section, the parts appearing as the same will show when the device is 35 in locked condition; Fig. 3 is a view similar to Fig. 2 but showing the parts as they will appear when the device is in unlocked condition; Fig. 4 is a cross section on the line 40 4—4 of Fig. 3; Fig. 5 is a plan of one of the permutation disks; Fig. 6 is a sectional detail of another permutation disk; Fig. 7 is an elevation of the permutation disk shown in Fig. 6; Fig. 8 is a plan of the means 45 whereby the permutation disks are yieldably held against rotation.

In carrying out the present invention there is provided a case 1 having an opening 2 and provided in one edge with a recess 3. A shackle 4 is pivoted as indicated at 5 to the case 1 and the free end of the shackle is adapted to enter the opening 2 to coöperate with locking mechanism hereinafter described. The free end of the shackle 4 is 55 equipped with a jaw 6.

At this point it may be stated that al-

though the structure is shown in the form of a padlock, the essential principles of the invention may be embodied in a lock of any other form and the invention is not confined to a padlock. 60

Located within the case 1 and supported upon a pivot element 7 is a dog 8 having a jaw 9 which coöperates with the jaw 6 of the shackle 4. The dog 8 terminates in a reduced finger 10 loosely received in an opening 11 formed in an actuating member 12 taking the form of a rod or bar, the actuating member having an angularly disposed extension 14. At one end, the actuating 65 member 12 terminates in a spindle 15 slidably received in one edge wall of the case 1 and projecting into the recess 3, there being a compression spring 16 surrounding the spindle 15, one end of the spring 16 abutting 70 against the case 1 and the other end of the spring abutting against the shoulder formed at the point where the spindle 15 merges into the body portion of the actuating member 12. The actuating member 12 75 is mounted to slide in a bracket 17 which projects from one wall of the case 1.

A permutation disk 18 is journaled for rotation on a thimble 19 having a slot 20 in one end receiving a fin 21 projecting from 80 the case 1, the construction being such that although the thimble 19 may have an end-wise movement, the same cannot rotate. As shown in Figs. 6 and 7, an annular recess 22 is formed in one face of the permutation 85 disk 18 and projecting into this recess 22 from the edge or flange portion of the disk 18 is a cam 23. Projecting from the thimble 19 is a lug 24 adapted to move in the recess 22 and to coöperate with the cam 23 90 under circumstances to be pointed out hereinafter. Other thimbles 25 are alined with the thimble 19 and each thimble 25 is provided with a radial lug 26. Journaled on each thimble 25 is a permutation disk 27, 100 each disk 27 having a recess 28 adapted to receive the corresponding lug 26 on the thimble 25. As shown in Fig. 1 there are slots 29 in the case, through which slots the permutation disks 18 and 27 protrude. 105

The invention includes a plate 30 shown in Fig. 8 in detail, the plate being secured to one side wall of the case 1 and having arms 31 terminated in fingers 32, each arm 31 being resilient and the fingers 32 being 110 adapted to coöperate with indentations 38 formed in the disks 27. The peripheries of

the disks 27 and 18 are provided with characters 33. Any number of characters 33 may be provided but there should be as many characters as there are indentations 38 in the permutation disks. The thimbles 25 are mounted on a spindle 34, one end of which is threaded as indicated at 35 into the end thimble 19. The spindle 34 includes a neck 36 adapted to bind against the end 10 face of the left hand thimble 25, reference being had to Figs. 2 and 3. The neck 36 of the spindle 34 terminates in a head 37. This head 37 preferably is of octagonal outline and it registers between the walls of the recesses 3 in the case 1 to prevent the spindle 34 and parts carried thereby from rotating under certain circumstances which will be set forth hereinafter. Because the permutation disks 18 and 27 are received in the 20 slots 29 in the case 1, the case and its slots constitute a means for holding the disks against participation in the endwise or longitudinal movement of the shaft above defined. The spindle 34 and the thimbles 25 and 19 constitute a shaft which is mounted to slide longitudinally upon the fin 21 but is held thereby against rotation.

When the shackle 4 is in the locked position shown in Fig. 2, the jaw 6 on the 30 shackle coöperates with the jaw 9 on the dog 8, these parts being so shaped that the dog 8 cannot be tilted on the pivot 7 when the shackle 4 is drawn upon. The finger 10 of the dog 8 lies in the opening 11 of the actuating member 12 and the actuating member 12 is pushed to the right by the action of the spring 16. The extension 14 of the actuating member 12 abuts against the lug 24 on the thimble 19 and the lug 24 lies in the annular recess 22 of the permutation disk 18 to one side of the cam 23. The lugs 26 of the thimbles 25 engage the side faces of the permutation disks 27 to one side of the recess 28 therein. It is therefore evident that 45 the shaft comprising the spindle 34 and the thimbles 19 and 25 cannot be pulled to the left in Fig. 2 and consequently, the actuating member 12 cannot be moved to the left, and therefore the dog 8 will remain engaged with the shackle 4. In order to open 50 the lock, the permutation disks 27 are rotated until a predetermined set of characters 33 thereon are in alignment transversely of the case 1. By this operation, the recesses 55 28 in the disks 27 will be lined up to receive the lugs 26 on the thimbles 25 when the latter are moved endwise along with the spindle 34. After a part of the combination has been set up by the permutation disks 27, 60 the disk 18 is rotated to set up the final character of the combination. When the disk 18 is rotated, the cam 23 thereon will engage the lug 24 on the thimble 19 and move this thimble, along with the thimbles 25 and the spindle 34 to the left, as shown in

Fig. 3, the lug 24 engaging the extension 14 of the actuating member 12 and moving the latter to the left, the dog 8 being tilted on its pivotal mounting 7 so that the jaw 9 on the dog is moved out of locking relation 70 with respect to the jaw 6 on the shackle 4. Then, the shackle 4 may be swung into the open position shown in Fig. 3.

When the lock is in open position shown in Fig. 3 and when the head 37 of the spindle 34 lies beyond the perimeter of the case 1, the spindle may be rotated through the medium of the head, thus loosening the threaded engagement indicated at 35 between the spindle and the thimble 19. Since 80 the thimbles 25 are now loose on the spindle 34 and since each thimble is interlocked through the medium of the lugs 26 and the recesses 28 with one of the permutation disks 27, each disk may be rotated in order to permit the combination to be changed. Then the spindle 34 is rotated so that the neck 36 binds against the endmost thimble 25, the thimbles being held in their adjusted positions, the thimbles and the spindle 34 90 becoming again, to all intents and purposes, an integral structure capable of endwise movement only.

When the parts are disposed in the locked condition shown in Fig. 2, the flat sides of the head 37 on the spindle 34 are engaged with the side walls of the recess 3 in the case 1. Therefore, the spindle 34 cannot be threaded out of the thimble 19 to effect an unauthorized opening of the lock. 100

The function of the plate 30 together with its spring arms 31 and fingers 32, engaging the recesses 28 of the permutation disks 37 is to hold these disks yieldingly in place while the combination is being set up as one 105 disk after another is rotated.

Having thus described the invention, what is claimed is:—

1. In a permutation padlock, a case; co-operating elements comprising a shaft 110 mounted for endwise movement in the case and a permutation disk journaled on the shaft, one of said co-operating elements having a lug, the other of said co-operating elements having a recess adapted to receive the 115 lug; a second permutation disk supported for rotation in the case; interacting parts carried by the second disk and the shaft for moving the shaft endwise when the second disk is rotated; means for holding both 120 disks against participation in the endwise movement of the shaft; and locking mechanism independent of the shaft and actuatable by direct contact with that interacting part which is on the shaft, when the shaft is 125 moved endwise.

2. In a permutation lock, a case; a shaft mounted for endwise movement in the case and provided with lugs; a permutation disk journaled on the shaft and having a recess 130

adapted to receive one lug; a second permutation disk supported for rotation in the case and provided with a cam adapted to engage the other lug to impart endwise movement to the shaft when the second disk is rotated; means for holding both disks against participation in the endwise movement of the shaft; and locking mechanism independent of the shaft and actuatable by 10 contact with the said other lug.

3. In a permutation lock, a case; coöperating elements comprising a shaft mounted for endwise movement in the case and a permutation disk journaled on the shaft, one of 15 said coöperating elements having a lug, the other of said coöperating elements having a recess adapted to receive the lug; a second permutation disk supported for rotation in the case; coacting means carried by the second 20 disk and the shaft for moving the shaft endwise when the second disk is rotated; means for holding both disks against participation in the endwise movement of the shaft; an actuating member mounted to 25 move in the case and engageable by the shaft when the shaft is moved endwise; and a locking dog operatively connected with the actuating member and supported by the case.

4. In a permutation lock, a case having a 30 recess; coöperating elements comprising a shaft mounted for endwise movement in the case and a permutation disk journaled on the shaft, one of said coöperating elements having a lug, the other of said coöperating 35 elements having a recess adapted to receive the lug; a second permutation disk supported for rotation in the case; coacting means carried by the second disk and the shaft for

moving the shaft endwise when the second disk is rotated; means for holding both disks 40 against participation in the endwise movement of the shaft; the shaft including a polygonal portion adapted to register in the recess of the case to hold the shaft against rotation.

5. In a permutation lock, a case; a secondary thimble mounted to move endwise in the case and held against rotation; a secondary permutation disk journaled on the thimble; interengaging elements on the disk 50 and the thimble for moving the thimble endwise when the disk is rotated; a primary thimble; a primary permutation disk journaled on the primary thimble; interengaging elements on the primary disk and on 55 the primary thimble and comprising a lug and a recess; a spindle threaded into the secondary thimble and supporting the primary thimble, the spindle having a head co-operating with the primary thimble to bind 60 the thimbles together; locking mechanism actuatable when the spindle is moved endwise; and means for preventing the permutation disks from participating in the endwise movement of the spindle; the case being provided with a recess into which the head of the spindle is adapted to retire to hold the spindle against rotation in the secondary thimble.

In testimony that I claim the foregoing 70 as my own, I have hereto affixed my signature in the presence of two witnesses.

MAX MEEPOS.
